UNITED STATES PATENT OFFICE.

ANDREW H. RUSSELL, OF WASHINGTON, DISTRICT OF COLUMBIA.

BREECH-LOADING GUN.

No. 816,607

Specification of Letters Patent.

Patented April 3, 1906.

Application filed June 22, 1905. Serial No. 266,472.

To all whom it may concern:

Be it known that I, ANDREW H. RUSSELL, of the United States Army, a citizen of the United States, stationed at Washington, District of Columbia, have invented certain new and useful Improvements in Breech-Loading Guns, of which the following is a specification.

This invention relates to breech-loading guns.

The object of the invention is to produce a breech-loading gun of a bolt or similar type in which the handle-pull shall be nearly in a straight line, but the bolt shall be locked by a partial rotation on its axis impelled by the handle movement; and the invention consists in certain constructions and combinations of parts, as will be explained, whereby the above-stated result is accomplished and whereby a gun of any caliber is adapted for rapid and convenient use either as a single-loader or preferably as a magazine-gun.

Figure 1 is a top plan of so much of a magazine-gun of the "bolt" type as will illustrate the principles of my invention, the bolt being closed. Fig. 2 is a side elevation of the same mechanism, the bolt being open. Fig. 3 is a view similar to Fig. 2, showing the bolt closed and parts broken away to exhibit the bolt-lock. Fig. 4 is a cross-section on line 4-4, Fig. 3. Fig. 5 is a broken cross-section on line 5-5, Fig. 3, showing cartridge-clip. The direction of view in each section is indicated by arrows, Fig. 3. Fig. 6 is a broken top plan of so much of the bolt-housing as illustrates the principles of the non-obstructible gearing. Fig. 7 is a top plan of bolt, handle, and connections detached. Fig. 8 is a bottom plan view of Fig. 7. Fig. 9 is a bottom plan view of handle detached. Fig. 10 is a bottom plan of handle with non-obstructible gearing. Fig. 11 is a front end view of bolt and handle. Fig. 12 is an end view of sleeve and handle-pivot from rear. Fig. 13 is a broken view of rear part of sleeve and pivot. Fig. 14 is a side elevation of cartridge-clip. Fig. 15 is a vertical section through the receiver, showing trigger engagement with hammer or striker. Fig. 16 is a broken side view of that part of the gun needed to show the handle-lock and safety device. Fig. 17 is a cross-section on line 17-18, Fig. 15, showing bolt in one position; and Fig. 18 is a section on the same line, showing the bolt in another position.

The stock shown is indicated at 1. This and the barrel 2 may be of any construction adapted for the purpose. The receiver, shoe, or frame 3 may be of form suitable for the reception of the bolt or breech-piece. The frame 3 has a recess 4 just in the rear of the barrel, into which recess the lugs on the bolt-front enter and in which they turn to lock the bolt against recoil, after the manner of the well-known bayonet-fastening and as is well known in bolt-guns. Shoulders 5 in the frame, behind the locking-lugs on the bolt, serve to hold the bolt against recoil, and longitudinal slots 6 allow the lugs 11 to pass forward and back when unlocked and to prevent the bolt from turning during this movement. As this bolt-lock is preferably at the front of the bolt and just in rear of the cartridge, the bolt does not yield by its own elasticity, as would a rear locking-bolt. The bolt 10 is generally cylindrical in form and is provided at its front end with locking-lugs 11, which lugs enter the recesses 4 when the bolt closes and lock behind the shoulders 5 when the bolt turns on its axis. The extractor 12 is of well-known construction and is held to the bolt in usual manner.

The parts described as not of my invention are merely typical and others might be substituted.

The bolt illustrated is hollow, as usual, to contain the firing pin and spring. The firing-pin and its head 13 constitute the hammer for exploding the cartridges. The sleeve 31 is non-rotating, as usual. Near the rear end of the bolt there is a rigid pintle 15 projecting from the side of a rotating part of the bolt. On this pintle an irregular segmental gearing 16 is pivoted. A hand-lever 17 is rigid with the gearing 16 and a handle 18 is rigid with said hand-lever. At the rear of the receiver there is a housing 20, through which the bolt passes. At the rear of this housing there is a curved rack or gear 21, with the teeth of which the teeth of the segment-gear 16 engage to rotate the bolt proper.

The segment-gear 16 has a notch 19, which, as shown, is at the same side of the segment-gear 16 as is the lever 17. The teeth of the segment-gear 16 engage with the rack-teeth of gear 21 when the bolt is closed. When the bolt is in locked position, Figs. 1 and 3, the lower tooth of segment-gear 16 is in engagement with the lower tooth of rack 21. In this position a rearward pull on the handle

18 causes the segment-gear 16 to turn and ride up the rack 21, the teeth engaging successively, thus turning the bolt on its axis, the gear 16 turning on pintle 15. The hand-lever 17 is thus given a peculiar compound movement, which is substantially to the rearward, but upward as well. A pull directly to the rear on handle 18 causes the lever 17 to partake of this compound movement. The turning of the bolt on its axis cams back the hammer 13 by means of an interposed non-rotating sleeve 31, as is common. The bolt is itself drawn back slightly as the segment-gear 16 rides up rack 21 by the engagement of pintle 15 on the bolt with the incline 33 at the rear of housing 20. This gives the bolt a powerful backward impulse to start the cartridge as well as to cock the hammer. Of course the form of locking-shoulders 5, or whatever locking means is used, may be such as to permit this backward impulse of the bolt.

The lever 17 is preferably integral with segment 16 and has a lug 34, which swings against the side of hammer-nose 35 in the opening movement described when the bolt has rotated so far as to be unlocked. The hammer is held from turning with the bolt by engagement with the receiver or with some non-turning part of the bolt. The hammer has at this time been cammed back slightly beyond its cocked position by the movement of the lever through the agency of the cam 90 on the lever bearing against the non-rotating sleeve 31 of the bolt. By the action of the firing-spring the hammer is pressed forward so that its nose enters notch 19 in the segment-gear 16 as soon as cam 90 has moved far enough to permit this movement. The nose of the hammer also enters notch 99 in the rear of the bolt. When the hammer or striker is in this position, the lever 17 cannot be swung sidewise in either direction, since it is held by the hammer, and the hammer cannot turn on the bolt by reason of the engagement just described. The continuation of the backward pull of the handle carries the lever and bolt to open position, Fig. 2. The swinging movement of the handle-lever merges into the longitudinal movement so gradually that the movement of the hand is practically continuous, and a backward pull on the handle involuntarily resolves itself into the swinging and then straight backward movement of the hand required to unlock and open the bolt, the segment 16 moving back away from rack 20 on the housing as the bolt moves back. The backward movement of the bolt extracts any cartridge or shell and ejects the same, as usual. Then, if the magazine be charged and turned on, a forward movement of the bolt carries another cartridge into the firing-chamber. In closing the bolt forward pressure is applied to handle 18 when in the po-

sition shown in Fig. 2. The lever 17 is held in its rigid relation with the bolt until the bolt is nearly closed, as above stated. At such time the hammer is caught by the trigger or sear, as usual with guns of this general character, and held back, releasing its nose from notch 99 of the bolt and allowing the handle to turn. The segment 16 has then been brought again into engagement with rack 21 and the handle swings forward and downwardly, reversing the rotary movement of the bolt by means of the engagement of segment 16 with rack 21. The same rotary movement locks the bolt. The turning of the bolt in closing may be a cam movement, which forces the cartridge home in its chamber, as is common. When the handle-lever has moved to such position that the bolt is fully locked, a projection 37 on the handle strikes an abutment 38 on the gun-stock and the parts are in compact relation, preventing an outward movement of the handle due to any blow. The initial opening movement of the handle must be guided by abutment 38.

A curved guide 74 preferably projects up from the frame at the right side in rear of the housing 20 and in rear of the pintle 15 when the bolt is in its closed position, as in Fig. 3. The object of this guide 74 is to serve as a bearing for the projection 34 from the segment 16 just before the change from rectilinear to rotary movement of the bolt, and vice versa, and at a time when the lever and segment are not rigidly held by the hammer. Guide 74 is more particularly advantageous in closing the bolt to prevent any accidental slip, lost motion, or binding of the gear-teeth. This guide is not absolutely essential.

In order that the gun may be carried in "safety" position and the firing may be thoroughly controllable, I provide means for stopping, holding, and releasing the bolt and bolt-handle. An example of such mechanism is illustrated more particularly in Figs. 2, 3, 15, and 16.

A spring-lever 101 at the side of the stock has a projection 102, which lies a little in front of the position of the hand-lever 17 when the bolt is closed. When hand-lever 17 in the bolt-closing movement strikes this projection 102, the locking movement is stopped. At this instant the trigger 103 is in the position shown in Fig. 15. This trigger 103 is pivoted in a trigger-bar 104, which bar is pivoted in the receiver. The front end of bar 104 is normally pressed down and the rear pressed upward by spring 105. The sear 106 on the rear of the trigger-bar engages the hammer to hold it cocked, as in Fig. 15. The trigger-bar stop 107 must move upward in order that the sear 106 may move downward. Bolt 10 has a notch or groove 110 in its body, which notch comes over the end of stop 107 when the bolt is fully closed. When not quite closed, as in

Fig. 17, the stop 107 cannot rise, and consequently the sear 106 cannot move down to release the hammer. Consequently a pull on the trigger is ineffective to fire the gun 5 when the bolt is stopped in the position of Fig. 17, which stoppage results from the engagement of the handle-lever with projection 102. Thus the bolt may be nearly closed and readily opened when the spring-lever 10 101 is in position to project the part 102. A turn-button or catch 112 on lever 101 serves to hold said lever in depressed position when turned as in Fig. 2. Then the lever-handle 15 will ride over projection 102 without obstruction and the bolt can be closed and the trigger effectively pulled to fire the gun. (See Fig. 3.)

20 A catch 115 is pivoted to the side of the stock, as illustrated, and this catch can be 25 swung out so as to hold up the lever 101 and lock the handle-lever securely between the projection 102 and this catch 115 when it is desirable that the gun shall neither be fired nor the breech opened—as, for instance, while the gun is used during drill.

The segment-gear 16 and the rack 21 are so calculated with relation to each other that the teeth are in smooth working relation in all positions. In most of the figures of drawings the teeth of segment 16 are shown as projecting from a hub or lever 17. This is not, however, the preferred form of construction. In Fig. 10 the teeth 61 are shown as projecting from a fan-shaped extension 62 of the end of lever 17. This covers the outer face of the segment-gear and leaves a space around each tooth 61 through which dust, grit, &c., may escape. Such a gearing I call "non-obstructible." In like manner the 30 teeth of rack 21 may be made with spaces entirely around them, as shown at 66, Fig. 6. The principle of operation is the same, but in the modification last described there is a better provision for the escape of dirt from the 35 gears.

The locking-lugs 11 and the abutments with which they engage are shown at the front end of the bolt, this being considered the best form of breech formature. It is, 40 however, apparent that the locking movement might be farther back on the bolt, as is common.

The handle is shown on the right-hand side of the gun, this being the most convenient position for a right-handed man. The 45 principles may be applied in other localities.

As shown in Figs. 1, 2, 3, 5, and 16, the rib or shoulder 70 at the front of housing 20 is on a curve of less diameter than is said housing. 50 It is also lower than shoulder 71 on the left side of the frame.

The clip designed for use with this gun is shown in Figs. 5 and 14 and is well known in this art. When the soldier, acting in haste 55 or in the dark, desires to apply a new clip or

package of cartridges to his gun, he brings the rear face of the clip against the front face of housing 20 at any place near shoulder 70, and by the sense of feeling he can easily 60 guide the clip along said housing and over said shoulder 70, and in so moving to the left the clip will be stopped by shoulder 71, when it can be easily moved down to its seat in the receiver, the ears on the clip being stopped in the vertical notches in shoulders 70 71. 75 Such notches and ears are common in the well-known Mauser gun.

I have shown my invention as applied to the well-known Mauser gun; but it should be understood that it is applicable to very many 80 bolt and magazine guns of different construction. With very little alteration of parts such guns can be changed into what becomes practically "straight-pull" bolt-guns. An advantage is that a much more rapid movement in opening and closing the breech may be attained. The operator has a vastly-increased leverage in starting the cartridge or shell backward in the gun and in locking the bolt on a "tight" cartridge. The hand 85 movement is easy and natural instead of the strained movement of a side-turning locking-handle, such as is used in a great number of bolt-guns.

The segment-piece 16 has an interior fin or 90 spline 91, which enters a slot 81 in the side of pindle 15. Slot 81 is longitudinal, and slot 82, communicating with it, is partly circumferential of the pindle. The handle-piece is applied to the pindle and turns thereon with 95 spline 91 of the circumferential part of the slot 82. While the gear-teeth are in engagement the handle cannot swing far enough to bring the fin or spline 91 opposite the longitudinal part 81 of the slot in the pindle. 100

The bolt, with its handle, can be removed from the gun by throwing back catch 95, which is the bolt-catch of the Mauser gun. When the segment-gear 16 is free from the 105 gears on the housing, as when the bolt is drawn back, the hammer 35 may be drawn back by hand to release its nose from notch 19. The handle can then be turned around until spline 91 is opposite straight slot 81, when the handle can be removed from the 110 pindle. 115

What I claim is—

1. In a breech-loading gun, a bolt and means for locking the same by a partial rotation, a pivot carried by said bolt and extending in a line transverse to the axis of the bolt, a handle-lever turning on said pivot and provided with a segment-gear, and a gear on the frame with which said segment engages to rotate the bolt. 120

2. In a breech-loading gun, a bolt having a rotating locking portion and a non-rotating portion, a handle-lever connected to the rotating portion by a pivot extending in transverse direction, a segment-gear rigid with the 125 130

handle-lever, and gear-teeth on the frame with which said segment engages to rotate the bolt.

3. In a bolt-gun, the bolt provided with locking-lugs at its front end, a frame with which said lugs engage to hold the bolt against recoil, a handle on the bolt having gear-teeth, and the frame having gear-teeth with which said teeth on the handle engage, for turning the bolt and locking and unlocking the same.

4. The combination, in a bolt-gun, of a frame having recoil-resisting abutments, a bolt having rigid lugs which engage said abutments to lock the bolt, a pindle on the bolt 15 extending laterally and having a segment-gear and a handle connected thereto, and a gear on the frame with which said segment engages to lock or unlock the bolt.

5. In a bolt-gun, the combination of a bolt having rigid lugs projecting radially near its front end, a frame having recesses to receive said lugs and abutments against which the lugs hold in resisting recoil, a segment-gear pivoted to the bolt and actuated by a handle 20 rigid with the gear, and a geared housing on the frame with which said segment engages to rotate the bolt.

6. In a bolt-gun, the combination of a frame provided with recesses and recoil-taking abutments near the breech of the barrel, a bolt having rigid lugs near its front end to engage said abutments, a rigid pindle extending laterally near the rear of the bolt, a segment-gear pivoted on said pindle and having 25 a rigid handle, and a housing on the frame having teeth with which the segment-teeth engage to rotate the bolt in locking and unlocking.

7. In a bolt-gun, the combination with the 40 bolt having a radial pindle, of a handle-lever pivoted to said pindle and a segment-gear moving with the handle, a housing on the frame with which said gear engages to rotate the bolt, and a stop-piece to limit the rotary 45 movement of said handle in unlocking the bolt.

8. In a bolt-gun, the combination of a bolt having locking-lugs, a frame with which said lugs engage, a handle-lever connected to the 50 bolt and engaging the frame by a gear to rotate the bolt, and means for holding the handle in rigid relation with the bolt at the termination of the rotary unlocking movement.

9. In a bolt-gun, the combination of the 55 bolt and frame, a handle-lever movable relatively to the bolt and having gear-teeth engaging gear-teeth on the frame to turn the bolt, the hammer, and a notch on the handle-lever with which said hammer engages to 60 prevent movement of said handle-lever, substantially as described.

10. The combination of the frame, bolt, and handle pivoted to the bolt, and gears engaging the handle with the frame to rotate 65 the bolt, of a stop on the handle and gun to

limit the handle movement in locking the bolt.

11. In a bolt-gun, the handle-lever pivotally connected to the bolt, and a handle-guide piece on the stock with which the handle engages in closed position, to guide the initial movement of the handle in opening the breech.

12. The combination, in a bolt-gun, of a handle-lever pivoted to the bolt and having 75 gear-teeth, the housing having gear-teeth with which said gears on the handle engage to rotate the bolt, and a guide-piece on the frame against which a part of the handle may bear in turning the bolt during the closing movement.

13. In a bolt-gun, the combination with a turning part of the bolt, of a laterally-extending pindle thereon, a handle having segment-gear carried by said pindle, means for 85 holding the handle in fixed relation to the bolt during the longitudinal movement of the bolt, and a tooth-gear on the frame with which said gear engages to turn the bolt.

14. In combination with the turning bolt, 90 a pindle thereon having a longitudinal and circumferential slot, and a handle adapted to engage the frame in locking or unlocking the bolt having a fin which enters said slot and permits a partial rotation of the handle around 95 the pindle without permitting the removal while the fin is in the circumferential portion of the slot.

15. In a bolt-gun, the bolt having a side pindle slotted longitudinally and in a circumferential direction, the handle surrounding 100 said pindle and having a fin to enter said slot, and means to hold the handle against movement around said pindle to permit the escape of the fin from the longitudinal slot.

16. In a bolt-gun, the combination with a rotating bolt and means for turning the same on its axis, of a movable stop automatically operating to obstruct the final closing movement of the bolt.

17. In a bolt-gun, the combination with a rotating bolt and means for turning the same in its closing movement, of a movable stop automatically operating to obstruct the final closing movement of the bolt, and means for 115 moving this stop out of working position.

18. In a bolt-gun, the combination with a rotating breech-bolt, of a movable stop adapted to be set to allow of the opening of the breech, and automatically operating to 120 obstruct the firing of the gun.

19. In a bolt-gun, the combination with a rotating breech-bolt and means for locking the same, of a movable stop adapted to be set to permit the opening of the bolt, automatic means by which the stop obstructs the closing of the bolt, and means by which this stop may be held inoperative.

20. The combination with the bolt-closing mechanism of a bolt-gun, of a stop auto- 130

matically moved into position to obstruct the final bolt turning and closing movement, and means for rendering said stop inert.

21. In a bolt-gun, the frame having a housing over the bolt and provided with a rib facing toward the barrel, a shoulder at one side of the receiver in front of and below said rib, a shoulder at the opposite side of the receiver projecting above the first, and a receptacle for the cartridge-clip between said shoulders, whereby the clip may be guided to its receptacle by said rib and stopped by the higher shoulder, when the bolt is retracted.
22. In a bolt-gun, the frame having a hous-

ing over the bolt and having a rib facing toward the barrel, shoulders in front of and below said rib, one of said shoulders being higher than the other, there being a recess for the loaded cartridge-clip between said shoulders, and notches in the shoulders to receive the edges of the clip in front of the retracted bolt.

In testimony whereof I affix my signature in presence of two witnesses.

ANDREW H. RUSSELL.
